Primary Examiner — Ian Simmons*Assistant Examiner* — Mark Cavanna(74) *Attorney, Agent, or Firm* — Oblon, McClelland, Maier & Neustadt, L.L.P.(57) **CLAIM**

The ornamental design for a pipette, as shown and described.

DESCRIPTION

FIG. 1 is a rear elevational view of my design for a pipette; FIG. 2 is a bottom enlarged plan view thereof; FIG. 3 is a top enlarged plan view thereof; FIG. 4 is a right side elevational view thereof; FIG. 5 is a front elevational view thereof; FIG. 6 is a left side elevational view thereof; and, FIG. 7 is a perspective view of the front, top, and right side thereof.

The broken lines in the drawings depict disclaimed subject matter and form no part of the claimed design.

1 Claim, 7 Drawing Sheets(56)
